UNITED STATES PATENT OFFICE.

HENRY HESS, OF PHILADELPHIA, PENNSYLVANIA.

PEN-FILLER.

1,179,921.

Specification of Letters Patent.

Patented Apr. 18, 1916.

Application filed July 17, 1911. Serial No. 639,068.

To all whom it may concern:

Be it known that I, HENRY HESS, a citizen of the United States, residing at Philadelphia, in the county of Philadelphia and 5 State of Pennsylvania, have invented certain new and useful Improvements in Pen-Fillers, of which the following is a specification, reference being had therein to the accompanying drawing.

- 10 My invention relates to pen fillers, and more especially an apparatus for filling that type of fountain pen known as the safety pen, which has an exterior screw thread near its forward end for the reception 15 of a screw closing cap, and the forward end or mouth of the pen being closable and openable by the protrusion and withdrawal of the pen point and parts carrying the same.
- 20 An object of the present invention is to afford a simple, cheap and effective filling apparatus and one in which the liability of spilling is minimized.

Other objects will appear hereinafter or 25 will be obvious.

The invention consists in the novel features, parts, combinations and apparatus shown and described hereinafter.

I will first describe several embodiments 30 of the present improvements, and will then set forth the features of novelty in the claims.

In the accompanying drawings, Figure 1 is an elevation partly in section of an apparatus embodying my improvements, with 35 a safety pen coupled thereto by its exterior screw threads, the parts shown in upright position with the pen protruding. Fig. 2 shows the same parts as Fig. 1 in inverted 40 position with the pen point withdrawn instead of protruding, this being the position in which the transfer of ink from the bottle to the pen occurs. Fig. 3 shows a screw cap that may be employed to close 45 the filler when not engaged with a pen. Fig. 4 shows a different embodiment of the present improvements, wherein a certain valve is employed for purposes that will be stated. Fig. 5 shows a still further embodiment. Fig. 6 shows an embodiment combining the features of Figs. 4 and 5, and 50 incidentally showing the parts of Fig. 5 in a different state of adjustment.

According to the present invention an 55 apparatus is contemplated in which the ink container or bottle, as it may be termed

whatever form it may take, has screw threads formed (preferably in an outlet member or portion) to enable the filler to be screw-connected to a pen; the screw threads shown as internal on the pen filler and external on the pen as would be the case with a safety pen. This mode of connection or coupling possesses great advantages including the security of connection which precludes accidental separation in the process of filling, as well as the tightness of connection which precludes leakage. The apparatus takes advantage of the existing screw threads on a pen for the purposes 60 65 70 75 80 85 90 95 100 105 110 hereof.

According to another feature of my invention, in addition to the bottle itself is an incompressible or inflexible outlet member which latter has means for coupling 75 it to a pen. This inflexible outlet member adds efficiency and convenience and enables the inverted pen and apparatus to be operated by a slight motion if necessary to cause a tendency of the ink to flow downward 80 from the bottle into the pen, thus dispensing with the need of any flexible or compressible outlet member for assisting the flow of ink, and greatly simplifying the apparatus.

Referring particularly to the form of Figs. 1, 2 and 3, A represents a bottle or any other container, and B an outlet member therefor, it being of an inflexible nature composed preferably of hard rubber and secured permanently in any desired manner to the bottle. The outlet member B provides for the apparatus an internal screw thread at b for engaging the screw threads of a safety or analogous pen. In the interior 90 of member B is a passage b' of sufficient size to permit not only a free transfer of ink but to accommodate the protruding pen point and permit its inward and outward movements. The outlet member B may have a chamfered seat b for the forward 95 end of the pen.

The fountain pen C is shown as having exterior threads at c' and a pen point c capable of being protruded and withdrawn in 100 any well known manner.

D represents a screw cap intended to be screwed into engagement with the thread b for the purpose of closing or corking the bottle when not in use.

The operation of the apparatus of Figs. 1 to 3 may be as follows: The screw cap D

will first be removed from the bottle and the pen C screwed into the position seen in Fig. 1. When the pen is tightly seated in the outlet member B the parts are ready for inversion to the position shown in Fig. 2. While in this position, the protruding pen point *c* will be withdrawn (although it might be withdrawn before inversion), thus opening the forward end or mouth of the pen for the reception of ink, which will flow by gravity from the bottle to the pen, the air within the latter bubbling up into the bottle as it is displaced by the down-flowing ink. By this operation not only is the pen filled but the pen point and surrounding parts are thoroughly rinsed which has an advantageous tendency to keep the parts clean and improve the action of the pen. As the force of gravity may not always be sufficient to cause the ink to flow downwardly and displace the air within the pen, a mechanical motion may be given to the apparatus, it being moved upwardly and downwardly by hand so as to assist the downward tendency of the ink and give it better opportunity to find its way into the pen, and for the air to escape. This effect it will be noted is brought about not by a change of air pressure in the bottle but by the different method of causing a disturbance of the liquid or causing portions of the liquid to be driven toward and into the pen with an increased force greater than gravity. Now with the parts still inverted the pen point will be again protruded to its full extent, thus closing the mouth of the pen. This in turn enables the apparatus to be re-inverted to the upright position of Fig. 1 when the pen may be uncoupled by screwing it out of place and the bottle recorked, which concludes the operation.

Referring now to the embodiment of Fig. 4 a variation is there indicated which will be useful as guarding against spilling caused by overfilling of a safety pen. The outlet member E in this embodiment is shown as containing a chamber together with means for opening the chamber to, and closing it from, the bottle A. To this end the outlet member E is shown as of increased length, a part of its interior passage, namely at *e*, constituting a chamber for the purposes referred to. At the upper end are the seat and coupling means for the pen as before. The chamber is comprised in the space between the pen C above and a valve F at a given position intermediate the pen and the bottle, said valve being preferably a rotary one shown as of conical form and having a passage *f* which may be in the closed position seen in Fig. 4 or in a position at right angles thereto to afford communication between bottle A and chamber *e*. The contents of the chamber *e* is calculated to correspond with the capacity of the pen so that precisely the

correct amount of ink for filling, but not overfilling the pen may be segregated from the body of ink prior to the opening of the pen for the reception of ink. The operation of this apparatus will be substantially as 70 with that of Figs. 1 to 3 save in the following respects, namely, that the valve F will be opened prior to or after the inversion of the entire apparatus and then closed prior to the opening of the pen mouth by the withdrawal of the protruding pen point. To assist the operation an air vent *e'* may be formed in the outlet member E communicating with a coöperating vent *f'* formed in one side of the valve F, so that air may 80 pass either inwardly or outwardly through vents *e'*, *f'* as the pressure existing within the chamber *e* may require. When not in use the valve F may be turned to closed position, thus preventing evaporation of the 85 ink in bottle A.

Referring now to the embodiment of Fig. 5, this is seen to retain the inflexible outlet member G, the apparatus operating on the same principles as the apparatuses of Figs. 90 1 to 3. There is some slight variation in the external screw threads of safety pens on the market, and until this is remedied some device may be desirable in my apparatus for accommodating it to the differently threaded pens. A portion of the outlet member containing the threads might be constructed of soft rubber so as to permit adaptation. I have, however, in Fig. 5 shown a device for coupling with the pen 100 by means of the circumferential compression of a soft thimble about the pen. H represents a soft rubber thimble of a form having a flange at *h*. An annular screw piece I with a slanted upper edge is engaged 105 with screw threads of a portion *g* of the outlet member so that turning said annular piece I will cause it to rise, this serving to press upon the projection *h* of the soft thimble and cause the latter to be pressed 110 inward or compressed circumferentially so as to inclose and contact the pen at every side, thus effecting a liquid-tight engagement between the pen and the outlet member. The parts are shown in Fig. 5 in open 115 position, and the embodiment of Fig. 6 shows substantially similar parts in closed position so as to indicate the effect of screwing the annular piece I upwardly.

Referring now to the embodiment of Fig. 120 6, this has an outlet member J which differs from the previously described outlet member in being formed to accommodate both the features of Fig. 4 and those of Fig. 5. Thus the valve F will be seen and also the 125 flexible thimble H, it being shown in closed position, the screw sleeve I being in its upward position.

The improvements above described have been found not only very effective but very 130

convenient, and have been found also to avoid the very general trouble existing in filling pens of the kind referred to, in the creation of bubbles and the consequent in- 5 complete filling, as well as the greater or less uncleanliness attending the operation.

While four specific embodiments of the present improvements have been illustrated and above described, it will be obvious that 10 many further changes in construction and form and in immaterial details may be made without departing from my invention, and I consequently do not wish to be limited to the illustrated forms as to details shown, 15 excepting as set forth in the below appended claims.

A merit of the above construction is that the pen, by reason of the nature of its connection with the bottle, is firmly held 20 against such deflection as will either permit leakage around the pen barrel, or allow the pen point to its injury contacting the interior of the filler, when in use.

What I claim and desire to secure by Letters Patent is:

1. Contrivance for filling the so-called safety type of fountain pen having a pen point capable of being withdrawn into and projected from the pen barrel, comprising 30 in combination a bottle, an outlet portion for said bottle, said outlet portion provided with means for so coupling it tightly to the pen barrel as to preclude leakage upon the inversion of the entire contrivance, said cou-

pling means being rigid whereby it holds 35 the pen against injurious deflection of its projecting point, and said outlet portion having a chamber of substantially the capacity of the pen, means as a valve for opening and closing the chamber, and an 40 air vent operable when the chamber is closed.

2. Contrivance for filling the so-called safety type of fountain pen having a pen point capable of being withdrawn into and 45 projected from the pen barrel, said contrivance consisting of a bottle having a special outlet portion constructed to be coupled tightly to the pen barrel so as to preclude leakage upon the inversion of the entire 50 contrivance, and said outlet portion and coupling being of rigid construction to hold the pen securely against injurious deflection of its projecting point; whereby the empty pen may be coupled to the said outlet portion with the pen point retracted, the pen and filling contrivance bodily inverted to cause the ink to flow into and fill the pen, the pen closed by projecting the pen point, without danger of injury, the pen and filling 55 contrivance bodily reinverted to upright position, and the filled pen uncoupled.

In testimony whereof I affix my signature in presence of two witnesses.

HENRY HESS.
